UNITED STATES PATENT OFFICE.

PETER WELIN, OF WORCESTER, MASSACHUSETTS.

TAKE-UP SPOOL AND RACEWAY FOR MECHANICAL MUSICAL INSTRUMENTS.

SPECIFICATION forming part of Letters Patent No. 637,540, dated November 21, 1899.

Application filed December 19, 1898. Serial No. 699,700. (No model.)

To all whom it may concern:

Be it known that I, PETER WELIN, of Worcester, in the county of Worcester and State of Massachusetts, have invented certain new and useful Improvements in Take-Up Spools and Raceways for Mechanical Musical Instruments, of which the following is a full, clear, and exact description.

This invention relates to a take-up spool of a mechanical musical instrument operated by a perforated music-sheet, its object being to provide a take-up spool that can properly receive or have wound thereon perforated music-sheets of different widths; and the invention also relates to the track or raceway over which the perforated music sheets travel in the operation of the instrument, provided with means for covering or closing and uncovering or opening a more or less number of the air-ducts at each end of the raceway, according to the width of the perforated music-sheet or the number of rows of perforations therein.

The invention consists of a novel construction of take-up spool for a mechanical musical instrument of that class wherein the spool is constructed and arranged so it can be adjusted as to its length—that is, the distance between its two heads—for the proper reception of different widths of perforated music-sheets and held to such adjustment, all substantially as hereinafter fully described; and the invention also consists of a raceway or track over which the perforated music-sheet is arranged to travel, having a series of air-ducts leading to the sounding devices, of means constructed and arranged to close and open any desired number of the air-ducts at each end of the raceway, according to the number of rows of perforations in the perforated music-sheet being used, all substantially as hereinafter fully described, reference being had to the accompanying sheet of drawings, in which are illustrated a take-up spool for a mechanical musical instrument and a raceway or track over which the perforated music-sheet travels, all constructed and arranged for operation in accordance with this invention.

Figure 1 is a side view of a take-up spool adapted to receive a perforated music-sheet of the full width of the length of the spool. Fig. 2 is a side view and partial longitudinal section of the take-up spool arranged to re-

ceive a perforated music-sheet of less width than the music-spool shown in Fig. 1. Fig. 3 is a plan view of the raceway having its row of air-ducts open its full length for a perforated music-sheet of the full width to be wound on the spool, as shown in Fig. 1, with means in plan view attached to the raceway-board for cutting off or closing the air-ducts at each end when a narrower sheet is to be used, or one with a less number of rows of perforations. Fig. 4 is a plan view of the raceway having its air-ducts cut off or closed at each end for a perforated music-sheet arranged to be wound thereon suitable for the take-up music-spool arranged as shown in Fig. 2. Fig. 5 is a cross-section shown on line 5 5, Fig. 2. Fig. 6 is a detail cross-section on line 6 6, Fig. 3. Fig. 7 is a detail cross-section on line 7 7, Fig. 4.

In the drawings, A represents a take-up music-spool for a mechanical musical instrument, on which the perforated music-sheet is wound in the operation of the instrument, formed of a spindle or body B, having journal-pins C, one at each end, a gear-wheel D, secured at one end, by which the spool is rotated, and a central hook E for the end of the music-sheet to be attached to the music-spool, all as usual in take-up music-spoons for such instruments and needing no more particular description herein, except as to the present invention.

Surrounding the spindle are two tubes or sleeves F G, adapted to freely slide longitudinally thereon a slight distance and turn thereon, each having a head or flange H secured thereto. Each tube is constructed of an inner tube J, of thin metal, and an outer tube or covering K, preferably of wood, secured thereto, which forms the surface of the music-spool on which is wound the perforated music-sheet.

In the inner end of each metal tube J is an angular slot or passage L through its thickness, extending longitudinally from the end M a short distance, the angular portion N of the slot in one tube extending in an opposite direction transversely to that of the slot in the other tube, as shown more particularly in Fig. 1.

Secured to the spindle are two radially-projecting pins P, which are so located that when the tubes are in the right positions and pushed toward each other the slots L will pass

over the pins P, and then turning each sleeve to the right or in opposite directions the right-
angular portions N will pass over their re-
spective pins into the positions shown in Fig.
5 2 and lock the sleeves from longitudinal move-
ment.

At one side of each slot L the end of the
metal tube is cut away, as at Q, on a diag-
onal line, so that when in the position shown
10 in Fig. 1 it will bear or be wedged against its
pin and lock the sleeve in its position, as
shown in Fig. 1.

On each end of the spindle is a small flange
or head R, which prevents the sleeves from
15 detachment therefrom and against which
they abut when moved outward into the po-
sitions shown in Fig. 1.

With the music-spool in the position shown
in Fig. 1 it is adapted to receive the wide
20 perforated music-sheet, having the larger
number of rows of perforations, and to put
the spool in position to receive the narrow
perforated music-sheet or the one having the
less number of rows of perforations, as shown
25 in Fig. 2, grasp the spool with both hands,
one on each sleeve, and turning them to the
right or in opposite directions the sides S of
the slots will abut against their respective
pins, then pushing the sleeves toward each
30 other the longitudinal portions travel over
the pins, and then turning the sleeves still
farther in the same direction the angular por-
tions N of the slots will pass over the pins
into the positions as shown in Fig. 2, when
35 the spool is in condition to receive the nar-
row music-sheet, and reversing the move-
ments the music-spool will be in condition to
again receive the wider music-sheet.

When using the wide music-sheet, all the air-
40 ducts a in the raceway T are used; but with
a narrow music-sheet it is necessary to cut
off or close a few at each end, as many as de-
sired, or according to the less number of rows
45 of perforations in the narrow music-sheet, and,
as shown in the present instance, three holes
at the end at the left and four holes at the end
at the right are closed, and this is accom-
plished as follows:

U is a flat triangular plate or valve pivoted
50 at b to the upper side of the raceway-board T
in a shallow recess d, so as to be below or
flush with the surface e of the raceway. The
plate U at the right end of the board is long
55 enough to extend over and cover four air-
ducts and the plate at the left to extend over
three air-ducts, and in each plate are a corre-
sponding number of holes f through its thick-
ness, which are so arranged that when these
60 plates are swung into the positions shown in
Fig. 3 its holes f will be over or coincident with
the air-ducts a in the raceway below them for
the air to pass through them when the wide
music-sheet is used, and when swung into the
65 positions shown in Fig. 4 the holes f will be
at one side of the air-ducts a and the solid
part of the plates will be over such air-ducts
and close them to the passage of air there-

through. The plates abut against the sides
g of their respective recesses to stop or hold
them in either position of their adjustment. 70

The inner ends of the wooden portion of the
sleeve are cut away, as at m, to leave space
for the free movement of the sleeves over the
pins. The cutting away of the end of the
75 metal tubes at Q allows the pins to be nearer
to the sleeves, by which in turning the sleeves
the other side S of the slots will abut against
the pins, and with the outer ends of the sleeves
against the shoulders R of the spindle the
80 sleeves are prevented from turning too far in
the wrong direction.

The sleeves can be made of one piece of ma-
terial; but it is preferable to make them of
two, as described, as it is better form of con-
struction for the operation of the music-spool. 85

Having thus described my invention, what
I claim is—

1. A take-up spool for a mechanical mu-
sical instrument, consisting of a spindle hav-
ing a shoulder at each end, two tubes or 90
sleeves over said spindle adapted to move
longitudinally back and forth thereon, two
pins projecting radially therefrom, a right-
angular slot in the inner end of each sleeve
arranged to engage respectively with the pins 95
when the sleeves are turned in the right direc-
tion and an inclined edge on the end of each
sleeve to abut or wedge against its respective
pin.

2. A take-up spool for a mechanical mu-
sical instrument, consisting of a spindle hav-
ing a shoulder at each end, a sleeve over the
spindle adapted to move longitudinally back
and forth thereon, the sleeve consisting of an
inner tube of metal and an outer tube or cov-
ering of other material secured together, a 100
right-angular slot in the inner end of the
metal tube, an inclined edge on the end of the
metal tube at one side of the slot, a pin pro-
jecting radially from the spindle in position 110
for the angular slot to pass thereover when
the tube is turned in the right direction and
for the inclined edge to abut or wedge against
the pin.

3. A raceway for a mechanical musical in-
strument having a row or line of air-ducts over
which a perforated music-sheet is arranged to
travel, a plate or valve on said raceway piv-
oted thereto and projecting over a number of
air-ducts at the end of the row or line having 120
holes or openings therethrough corresponding
to the air-ducts covered by the plate or valve,
by which the plate or valve can be moved to
open and close the air-ducts to adjust the
raceway to a wide or narrow perforated mu-
sic-sheet to be wound upon the take-up spool. 125

In testimony whereof I have hereunto set
my hand in the presence of two subscribing
witnesses.

PETER WELIN.
